ROTOR ASSEMBLIES FOR GAS TURBINE ENGINES

Stanley George Hooker and Kenneth William Clark, Bristol, England, assignors, by mesne assignments, to Bristol Aero-Engines Limited, Bristol, England, a British company

Application November 15, 1954, Serial No. 468,974

Claims priority, application Great Britain November 20, 1953

4 Claims. (Cl. 253—39.15)

This invention concerns rotor assemblies for gas turbine engines, which rotor assemblies are of the kind (hereinafter referred to as of the kind described) comprising a turbine rotor having a blade-carrying disc and a ring of turbine blades carried by the blade-carrying disc around its periphery, and a cooling-air-guide disc arranged for rotation co-axially with the blade-carrying disc, said cooling-air-guide disc defining with the blade carrying disc a space through which cooling air may pass from the region of the centre of the blade-carrying disc to the region of its rim.

Hitherto such cooling-air-guide discs have in some cases been welded at their rims to the blade-carrying disc, but this is not practicable with some materials or when it is desired that the cooling-air-guide disc should extend to a greater diameter than the tips of blade roots housed in slots extending from face to face of the blade-carrying disc. In other cases the cooling air guide disc has been clamped to a hub portion of the blade-carrying disc and has been provided with a ring of openings around the hub portion for the entry of the cooling air. This arrangement has the drawback that the cooling air openings cause high stress concentrations in the cooling-air-guide disc and also that at high rotational speeds of the rotor assembly air does not pass readily through the openings.

According to the present invention, there is provided a rotor assembly of the kind described, wherein the cooling-air-guide disc has a rim bearing against a substantially axially-facing surface on the turbine rotor and a central aperture by which it is drivingly mounted upon a member attached to the blade-carrying disc, which member is provided with passages through which cooling air can pass into said space.

According to a feature of the present invention, said member may have a ring of spaced radially-extending spoke-like projections, the spaces between said projections constituting said passages.

When the above mentioned feature is adopted it is preferred that the cooling-air-guide disc be drivingly mounted upon said spaced spoke-like projections. Preferably, also, when said spaced spoke-like projections are provided, said projections are so shaped in cross-sectional planes that during operation of the rotor assembly they act as vanes which promote air flow into the space between the blade-carrying disc and the cooling-air-guide disc.

According to another feature of the present invention, the cooling-air-guide disc may be a forging and said member may be a casting, the cooling air-guide-disc being an interference fit upon said member.

According to yet another feature of the present invention, the cooling-air-guide disc may be so shaped that during rotation of the rotor assembly the centrifugal force acting on the cooling-air-guide disc tends to maintain the rim of the cooling-air-guide disc pressed against

2

said substantially axially-facing surfaces on the turbine rotor.

A rotor assembly according to the present invention will now be described merely by way of example with reference to the accompanying drawings whereof:

Figure 1 is an axial section on one side of the axis of the rotor assembly,

Figure 2 is a developed partial section along the line II-II in Figure 1, and

Figure 3 is a partial end view in the direction of arrow 3 in Figure 1 with the cooling-air-guide disc removed.

Referring to Figures 1 and 2, the rotor assembly comprises a hollow shaft 1 provided with a coupling flange 2 attached by bolts 3 to a turbine rotor having a blade-carrying disc 4 and a ring of blades 10 carried by the disc 4. The disc 4 has a thickened hub portion 5 surrounding a central bore 6, the axis of rotation of the assembly being shown at 7. The disc 4 has slots 8 around its periphery and extending from face to face of the disc. In each slot is mounted, by its root 9, a blade 10. In the example being described, the roots 9 are of "fir-tree" formation, and the blades 10 have internal passages, not shown, to which cooling air is admitted through a bore 11 extending through the blade root from a port 12 in one axial end face of each blade root.

Cooling air passes from the region of the centre of the assembly to the ports 12 through a space 13 formed between the disc 4 and a cooling-air-guide disc 14 of annular configuration which is mounted coaxially with the disc 4 for rotation therewith and which has a rim 15 bearing against axially facing surfaces 16 (see Figure 3) formed on the turbine rotor. In the example being described, the surfaces 16 are formed on the end surfaces of those parts of the blade roots 9 which are disposed radially outward and axially forward of the peripheral edge of the disc 4 and are contiguous to form a continuous ring. The disc 14, therefore, extends to a greater diameter than the radially inner ends 9a of the blade roots 9. The disc 14 is of forged material and has a central aperture 17 which receives a member generally indicated at 18 attached to the disc 4 by the coupling bolts 3. The member 18 has an apertured central portion 18a. Since only a single aperture 17 has to be provided at the centre of the disc 14 the disc can be designed to avoid high stress concentrations during operation of the rotor assembly.

The member 18 is formed around its periphery with a ring of equally spaced radially-directed spoke-like projections or vanes 19 the spaces 20 between which constitute passages for cooling air to pass into the space 13, and the disc 14 is shrunk upon the outer ends of the spoke-like projections so that the inner periphery of the disc engages the outer ends of the projections, the disc thereby being supported on said projections for rotation with said member. The projections 19 are machined to give them, in cross section, a vane or blade form such as that shown in Figure 2 which will promote the passage of air between them when the assembly is in operation and rotating at high speed in the direction of the arrow 21, and the disc 14 is preferably mounted directly upon the radially outer ends of the projections, i.e. without an intermediate rim, as shown so that this machining operation is facilitated. As the member 18 is of comparatively small diameter and therefore unlike the disc 14 is not subjected to very great centrifugal stresses during operation of the rotor assembly, it is conveniently made as a casting in a suitable material of sufficient tensile strength.

To ensure that centrifugal forces acting upon the disc 14 when the rotor assembly is in operation tend to maintain the rim 15 of the latter pressed against the end sur-

faces of the blade roots that form surfaces 16, the disc 14 is slightly dished towards the disc 4 so that radial mid-thickness lines, such as 22, of the disc 14 diverge from radial lines, such as 23, which are perpendicular to the axis of rotation 7 and pass through the outermost mid-thickness points of the disc 14, such as 24, towards the disc 4 on the side of the mid-thickness points nearer the axis of rotation 7. In determining the outermost mid-thickness points such as 24 it is to be understood that the local thickening of the rim 15 is disregarded.

We claim:

1. For a gas turbine engine, the combination with a turbine rotor comprising a blade-carrying disc having an outer periphery and a hub portion and a ring of turbine blades carried by said blade-carrying disc round its periphery, each of said turbine blades having a substantially axially-facing surface adjacent the outer periphery of said disc, of a member attached to said blade-carrying disc coaxially therewith, a cooling-air-guide disc spaced axially from said blade-carrying disc, said cooling-air-guide disc being of annular configuration and having a rim bearing freely against said axially facing surfaces and having only a single central aperture providing the cooling-air-guide disc with an inner periphery within which said member is located, the inner periphery of said cooling-air-guide disc engaging and supported on said member for rotation with the member, said cooling-air-guide disc, said member and said blade-carrying disc together defining a space through which cooling air may pass from the region of the hub portion of said blade-carrying disc to the region of said axially-facing surface of each blade, said member having passages adjacent said hub portion through which cooling air can pass into said space, said cooling-air-guide disc being dished towards said blade-carrying disc whereby during rotation of the turbine-rotor-member blade-carrying disc assembly the centrifugal force acting on the cooling-air-guide disc tends to maintain the rim of the cooling-air-guide disc pressed against said axially facing surfaces of the blades.

2. The combination as claimed in claim 1, wherein radial mid-thickness lines of the cooling-air-guide disc diverge, from radial lines perpendicular to the axis of said turbine rotor which pass through the outermost mid-thickness points of the cooling-air-guide disc, towards said blade-carrying disc on the side of said mid-thickness points nearer the axis of said turbine rotor.

3. For a gas turbine engine, the combination with a turbine rotor comprising a blade-carrying disc having an outer periphery and a hub portion and a ring of turbine blades carried by said blade-carrying disc round its periphery, each of said turbine blades having a substantially axially-facing surface adjacent the outer periphery of said disc, of a member attached to said blade-carrying disc coaxially therewith, a cooling-air-guide disc spaced axially from said blade-carrying disc, said cooling-air-guide disc being of annular configuration and having a rim bearing freely against said axially facing surfaces and having only a single central aperture providing the cooling-air-guide

disc with an inner periphery within which said member is located, the inner periphery of said cooling-air-guide disc engaging and supported on said member for rotation with the member, said cooling-air-guide disc, said member and said blade-carrying disc together defining a space through which cooling air may pass from the region of the hub portion of said blade-carrying disc to the region of said axially-facing surface of each blade, said member having passages adjacent said hub portion through which cooling air can pass into said space, radial mid-thickness lines of the cooling-air-guide disc diverging from radial lines perpendicular to the axis of said turbine rotor which pass through the outermost mid-thickness points of the cooling-air-guide disc toward said blade-carrying disc on the side of said mid-thickness points nearer the axis of said turbine rotor.

4. For a gas turbine engine, the combination with a turbine rotor comprising a blade-carrying disc having an outer periphery and a hub portion and a ring of turbine blades carried by said blade-carrying disc around its periphery, each of said turbine blades having a substantially axially-facing surface adjacent the outer periphery of said disc, of a member attached to said blade-carrying disc coaxially therewith, said member comprising a central portion having a periphery and a ring of vanes carried on said central portion and spaced apart around its periphery, said vanes each projecting radially of said central portion, a cooling-air-guide disc spaced axially from said blade-carrying disc, said cooling-air-guide disc being of annular configuration and having a rim bearing freely against said axially facing surfaces and having only a single central aperture providing the cooling-air-guide disc with an inner periphery within which said member is located, the inner periphery of said cooling-air-guide disc engaging and supported on the outer ends of said vanes for rotating with said member, said cooling-air-guide disc, said member and said blade-carrying disc together defining a space through which cooling air may pass from the region of the hub portion of said blade-carrying disc to the region of said axially facing surfaces, said vanes, during rotation of the turbine rotor, promoting air flow into said space, radial mid-thickness lines of the cooling-air-guide disc diverging from radial lines perpendicular to the axis of said turbine rotor which pass through the outermost mid-thickness points of the cooling-air-guide disc towards said blade-carrying disc on the side of said mid-thickness points nearer the axis of said turbine rotor.
